UNITED STATES PATENT OFFICE

CARL BORNMANN, OF BINGHAMTON, NEW YORK, ASSIGNOR TO AGFA ANSCO CORPORATION, OF BINGHAMTON, NEW YORK, A CORPORATION OF NEW YORK.

ENLARGING APPARATUS

Application filed December 17, 1930. Serial No. 503,003.

This invention relates to the enlargement of pictures and more particularly to an apparatus for making enlarged positives directly from relatively small negatives.

5 One object of this invention is to provide an apparatus for making enlarged positives from negatives, with an efficient and easily operated lighting system.

Another object is the provision of a novel 10 apparatus for direct enlargement including a film guiding means.

These objects are accomplished by providing a compact apparatus having a source 15 of light, a holder for a negative, a holder for a sensitized surface upon which the enlarged positive is to be made, a lens system adapted to direct light from the source through the negative to the sensitized surface and an additional source of illumination providing a 20 dim light for loading and adjusting the apparatus.

The novel features which I believe to be characteristic of my invention are set forth with particularity in the appended claims. 25 The invention itself, however, together with further objects and advantages thereof will best be understood by reference to the following description and to the figures of the accompanying drawings in which:—

30 Figure 1 is a perspective view of a device embodying features of this invention,

Figure 2 is a side elevation, partly in section, of a similar device embodying features of this invention,

35 Figure 3 is a front elevation of that portion of the device shown in Figure 1 which supports a negative film, with the guiding means adjusted for a long, narrow, negative,

40 Figure 4 is like Figure 3 but with the guiding means adjusted for a wide, short negative,

Figure 5 is a top or plan view of a transparent negative holder used in the devices shown in Figure 1 and Figure 2,

45 Figure 6 is a cross sectional view of the holder shown in Figure 5 taken on line 6—6, and

50 Figure 7 is a circuit diagram showing electrical connections for the devices shown in Figure 1 and Figure 2.

In the several figures like reference characters indicate like parts.

Referring now to the drawings in detail and more particularly to Figures 1 and 2, reference character 1 indicates a base number, which may be made of any suitable material, having a substantially vertical support member 2. A lamp housing 3 is carried by support 2 and has a cover 4 to give access to its interior and to projection lamp 5 supported therein by means of lamp base 7. An adjustable lens mount 8, having either one or a plurality of lenses 9, is supported in a wall of lamp housing 3. A horizontal box-like support member 10, carried by vertical support member 2 is positioned adjacent housing 3 and provides a support for a second adjustable lens system 11 and photographic negative supporting means indicated generally at 12.

Negative supporting means 12 may comprise two transparent plates 14 and 15 illustrated on a larger scale in Figures 5 and 6. Plates 14 and 15 are hinged together by flexible member 16 which is secured to both plates and provides a space between plates 14 and 15 when said plates are parallel to each other. A film 17 or other negative may be clamped between plates 14 and 15, which are disposed on horizontal support 10 as shown in Figures 1 and 2. Spring members 18 may be secured to support 10 and press on the upper surface of plate 14 to hold film 17 securely between plates 14 and 15. Support 10 may be provided, on opposite sides thereof, with adjustable guide plates 19 each having a slot 20 therein to permit plates 19 to be raised or lowered relative to support 10. Plates 19 may be secured to support 10 in adjusted position by screws and washers 21 or by other suitable means. Each plate 19 has an upturned portion 22 to facilitate adjustment thereof. Each plate 19 also has a relatively wide groove or notch 23 in one end thereof so

that, when the grooved ends project above support 10, they provide guiding means for film 17. Grooves 23 should be slightly wider than film 17 so that the film may readily slide through them. Support 10 is provided with laterally extending members 24 and 25 to 95 100

keep the curled-up portions of film 17 widely separated, as clearly shown in Figure 3, so that said portions of the film will not interfere with the passage of light from lamp 5 to a positive sensitized surface 26.

Sensitized surface 26 may be provided by a sheet of paper or other suitable material having a light sensitive coating thereon. A holder or frame 27 is provided on base 1 for keeping surface or sheet 26 flat and in proper position relative to lenses 9 and 11. Frame 27 has its bottom partly cut away on the inner portions thereof to provide space for the edges of sheet 26 and has its bottom entirely cut away at one end as indicated at 28 so that photographic paper or other carrier of a sensitized surface 26 may be slipped into and out of the frame 27. Grooves or notches 29 and 30 in holder 27 and base 1 respectively may also be provided to enable the operator of the device to grasp sheet 26.

A lamp 31 and a socket 32 therefor are disposed on the opposite side of vertical support 2 from holder 27, the socket 32 being secured to base 1. The lamp 31 is preferably ruby colored and of low candle power. It is placed in back of support 2 so that its light will not fall directly on surface 26 but it should provide sufficient light for adjusting the apparatus.

Figure 8 shows diagrammatically the electrical connections for lamps 5 and 31 which are connected in series with each other and to a source of electrical energy 33. A switch 34 is connected in parallel with ruby lamp 31. The voltages and currents of lamps 5 and 31 should be such that, with switch 34 closed, lamp 5 will burn brightly but safely at the full voltage of source 33, and with switch 34 open, lamp 5 will give only a small amount of light of a dull red color and most of the voltage of source 33 will be impressed on lamp 31. Switch 34 may be provided with a knob 35, by turning which switch 34 may be quickly opened or closed.

The devices described above and shown in the drawing are operated as follows: With switch 34 open, lamp 5 gives only a dim red light and lamp 31 gives a ruby light which affect the photographic emulsion 26 very slightly. By the illumination thus provided the operator can place a negative film or plate between plates 14 and 15 and position them properly with respect to support 10 and lens systems 9 and 11. The operator can also place a piece of photographic paper in holder 27 and adjust lens systems 9 and 11 so that light from lamp 5 projects the image on the negative to surface 26 clearly and sharply. Switch 34 is then closed for a period of time to properly expose surface 26 and is then opened again. The photographic paper carrying the exposed emulsion 26 may then be developed in the usual manner and an enlarged positive print of the negative will be

obtained. If the negative is in the form of a strip of film, any picture on the film strip may be printed the desired number of times and then the strip may be pulled through grooves 23 in plates 19 and between transparent plates 14 and 15 until the next desired negative picture is in position for printing. If the negative is a wide film or plate the guides 19 are lowered relative to support 10 to provide an unobstructed surface on which the negative is positioned, either with or without the aid of plates 14 and 15.

Several embodiments of this invention have been described in the foregoing specification and illustrated in the accompanying drawings but it should be understood that the invention itself is limited only by the intent and scope of the appended claims.

I claim:

1. An apparatus for printing enlarged positives directly from negatives comprising in combination, a photographic negative film strip, supporting means therefor comprising a pair of guide plates having grooves in the ends thereof slightly wider than said film, said plates being disposed substantially perpendicular to that portion of the film which is in position to be printed, means for supporting a sensitized surface at a predetermined distance from said negative, a lamp, a pair of laterally extending members for keeping the remaining portions of said negative film out of the path of light of said lamp to the sensitized surface, means for supporting said lamp at a predetermined distance from said negative on the side thereof opposite said sensitized surface, means for projecting light from said lamp through said negative to said sensitized surface, a second lamp adjacent said sensitized surface, a source of electrical energy, and means whereby the first mentioned lamp may be connected to said source or both of said lamps may be connected in series to said source, as desired.

2. An apparatus for printing enlarged positives directly from negatives comprising in combination, a support having a horizontal member and a substantially vertical member, a lamp and a housing therefor carried by said vertical member, a holder for a light sensitive sheet on said horizontal member, a holder for a photographic negative carried by said vertical member and disposed between said lamp housing and the first mentioned holder, a system of lenses for projecting from said negative an image thereon to said light sensitive sheet, whereby light from said lamp causes an enlargement of said image to be printed on said sheet, said holder for the photographic negative including a box like horizontal member secured to said vertical member and having apertures in the top and bottom thereof, said apertures being aligned with said lens system, a portion of

said lens system disposed in the aperture in
the bottom of said box like member, a pair
of hinged transparent plates positioned on
the top of said box like member in alignment
with the aperture therein, said plates being
5 adapted to hold the photographic negative
therebetween, and in alignment with said lens
system, and a plurality of spring members
secured to said box like member and exert-
ing pressure on said plates and said negative
10 whereby said plates and said negative are
held in their adjusted positions.

In testimony whereof, I affix my signature.
CARL BORNMANN.
